Jonathan Pick, of New Britain, Conn.
Letters Patent No 1287, dated July 17, 1860

The schedule referred to in these Letters Patent and making part of the same

Dec. 1287

To all whom it may concern,

Be it known that I, Elmathan Peck, of New Haven, County of Hartford and State of Connecticut have invented or produced a new and original Design or Pattern for Gridiron, and I do hereby declare that the following is a full and exact description of the same, viz:

In the accompanying photographic view is shown a plain ornamental design or pattern for a Gridiron comprised of a combination of configurations of groove or channel bars b, nozzle c, hinge enlargement d, and handle e, constituting a plain ornamental pattern or design for a gridiron.

I claim the plain ornamental design or pattern herein described and represented in the accompanying photographic view for a Gridiron.

Witnesses,

A. P. Collins
N. B. Chamberlain.
